UNITED STATES PATENT OFFICE.

CHAUNCEY C. CLARK, OF PHILADELPHIA, PENNSYLVANIA, ASSIGNOR OF
ONE-HALF TO JAMES G. CARSON, OF PHILADELPHIA, PENNSYLVANIA.

ALCOHOLIC-LIQUID PURIFIER.

SPECIFICATION forming part of Letters Patent No. 710,669, dated October 7, 1902.

Application filed April 4, 1902. Serial No. 101,308. (No model.)

To all whom it may concern:

Be it known that I, CHAUNCEY C. CLARK, a citizen of the United States, residing at Philadelphia, in the county of Philadelphia and 5 State of Pennsylvania, have invented certain new and useful Improvements in Alcoholic-Liquid Purifiers, of which the following is a specification.

My invention relates to purifier mechanism for the treatment of alcoholic liquors for the purpose of removing therefrom all of the impurities and foreign substances carried in the liquid or held in suspension therein by electrolysis as the liquid enters the treating-receptacle after the first process of distillation, the withdrawal of the liquid from below its upper surface, where floating impurities arise, its after removal to a compartment preferably filled with charcoal for its 10 filtration, and the separation of impurities of equal specific gravity with the liquid and which have not heretofore been removed by electrolysis or floatage, and means for introducing and withdrawing the liquid, the 15 composed residue, the floatage, and the washing of the filter and its contents. The action of the apparatus is continuous during the supply of liquid and is automatic, as the electric current will flow in sufficient volume to 20 attack the volume of impurities as presented, be the same more or less, according to the purity of the inflowing liquid. It has been found that by using this mechanism only one distillation of the liquid is necessary, thus 25 effecting the saving of the cost of the second distillation and the time employed for that purpose. It has also been found that a perfectly pure liquor is produced by this mechanism and that it is no longer necessary to 30 consume the long interval of time before the liquor is "aged," which will be of great profit to the brewers of alcoholic liquors. Distillation does not wholly purify, as is proven by the fact that after distillation liquors must 35 be set away to decompose and purify by time, which time is saved by the employment of my mechanism.

My mechanism is illustrated in the accompanying drawings, in which—

50 Figure 1 is in general a central section with

some of the parts in elevation. Fig. 2 is an end elevation at the filter end.

Similar parts are indicated by similar reference characters throughout the views.

I employ a receptacle 1, which may be made 55 of oak when a cheap construction is desired; but when a more durable structure is required the cylinder 2 will preferably be of copper, as shown in the drawings. Near the left end of the receptacle 1 and through its top an inlet-chamber 2 is inserted. It has a flange 3, which supports it on receptacle 1, and above it a cover 4 is secured to the flange. The cover is provided with a neck 5, to which is secured an inlet 6, having an inlet-pipe 7 for 60 conveying the inflowing liquid. Above any suitable safety appliance may be secured for the purpose of preventing excessive hydrostatic pressure within the receptacle. The cover is also provided with insulated stuffing- 65 boxes 8 9, which permit the electrical conductors 10 11 to pass within the cylinder 2, while at the same time they prevent any liquid from passing out. The stuffing-boxes are of the construction fully set forth in my application 70 for liquid-purifier filed January 22, 1901, Serial No. 44,274. Within inlet-chamber 2 is an insulated lining 12. Conductors 10 11 are connected to a dynamo or source of electrical energy exterior to the receptacle, and within 75 chamber 2 they suspend a series of perforated disk electrodes, 13 being anodes, and 14 being cathodes, and their construction and suspension are fully set forth in my former application, as above referred to. The inlet- 80 chamber 2 has an open lower end, through which the liquid passes into receptacle 1 after its electrolysis, at which time the products of decomposition, which are of greater specific gravity than the liquid, will descend to 85 the bottom of the receptacle 1, and at convenient times the deposit can be drawn out of the receptacle by means of a series of pipes 15, controlled by valves 16 in connection with pipe 17, common to all. Toward the opposite 90 end of the receptacle from chamber 2 and mounted above the receptacle is a dome 18, within which arise the floating impurities above the level of the body of liquid, which 95 completely fills the receptacle 1. Inserted 100

through the top of the dome and entering the body of the liquid in receptacle 1 is an outlet-pipe 19. Beyond dome 18 the receptacle 1 has a partition or bulkhead 20, which with head 21 forms the filtering-compartment 22, with a screen 23 reaching across its upper part, below which the compartment is filled with charcoal or other suitable filtering material. From the top of dome 18 a delivery-pipe 24 passes upward, then outward and downward, and enters the bottom of compartment 22, and the entering fluid under pressure percolates through the interstices between the particles of filtering material, where the impurities are collected and retained, and the pure liquid passes above screen 23 and enters pipe 25 and is conveyed away ready for immediate use. A valve 26 controls pipe 24. Dome 18 has a surface blow-pipe 27, controlled by valve 28 for the removal of the floating impurities. A wash-out pipe 29 enters under compartment 22, and by its use the filtering material is cleansed. A head 30 closes the end of the receptacle opposite the filtering-compartment, and it is provided with a manhole 31 for gaining access to the interior of the receptacle. Filter-head 21 is likewise provided with a manhole 32, whereby filtering material may be inserted and removed.

I claim—

1. In a liquid-purifier, a horizontal cylindrical receptacle, an insulated lined inlet-chamber inserted therein, a series of perforated disk electrodes suspended in the chamber, electrical conductors therefor, a dome located on the receptacle for the collection of floating impurities, a filtering-compartment within the receptacle and means for conveying liquid to the inlet-chamber for electrolysis, thence to the receptacle, thence from a point below the top of the liquid in the receptacle to the filter, and from the filter to a desired place of delivery.
2. In a liquid-purifier, a horizontal cylindrical receptacle having means thereto attached for the electrolysis of entering liquid, means within the receptacle for the collection of floating impurities, means for the filtration of the liquid, and means for the introduction of the liquid for its electrolysis, and its removal after filtration.
3. In a liquid-purifier, a horizontal cylindrical receptacle having an inlet-chamber inserted therein, having an insulating-lining and a series of perforated electrodes, means

for the electrolysis of entering liquid, a compartment within the receptacle for filtration, filtering means in the compartment, and means exterior to the receptacle to remove the liquid after its electrolysis to the filtering-compartment for its passage through the filtering material.

4. In a liquid purifier and filter, a horizontal cylindrical receptacle having a portion thereof for the storage of filtering material, a chamber entering within the receptacle and for a series of perforated disk electrodes therein, a raised portion above the receptacle and opened thereto for the collection of floating impurities, means to withdraw the floating impurities, means entering the body of the electrolyte thereafter passing through and out of the raised portion and entering the filtering portion of the receptacle, and whereby the electrolyte shall pass through and be subjected to purification by filtration, and means to withdraw the electrolyte from the filter.

5. In a liquid-purifier, a horizontal cylindrical receptacle having a filtration-compartment, a head for the receptacle and for the filter, manholes in the heads, a liquid-passage from the receptacle to the filter; means to withdraw deposit from the receptacle at its lower side, means to wash out the filter, an inflowing-chamber for the receptacle, a series of perforated disk electrodes within the inflowing-chamber constructed to intercept the inflow and subject it to electrolytic action, and electrical conductors for the electrodes.

6. In a liquid-purifier, a horizontal cylindrical receptacle having a part thereof for the electrolysis of inflowing liquids, and within the said part a series of intercepting disk electrodes with electrical conductors therefor; another part of the receptacle for holding filtering material, a liquid-passage from the electrolytic portion to the filtration portion of the receptacle, a screen at the upper part of the filtration portion, and means to pass liquid within the receptacle for its electrolysis, thence to the filter portion for its filtration, and for its withdrawal from the filter, and above its screen, after its filtration.

In testimony whereof I affix my signature in presence of two witnesses.

CHAUNCEY C. CLARK.
